UNITED STATES PATENT OFFICE.

CLINTON S. ROBISON, OF CHICAGO, ILLINOIS, ASSIGNOR TO ALADDIN PRODUCTS COMPANY, OF CHICAGO, ILLINOIS, A CORPORATION OF ILLINOIS.

PROCESS OF MANUFACTURE OF DYE-SOAP.

1,353,182.

Specification of Letters Patent. Patented Sept. 21, 1920.

No Drawing.

Application filed October 25, 1917. Serial No. 198,402.

To all whom it may concern:

Be it known that I, CLINTON S. ROBISON, a citizen of the United States, residing at Chicago, in the county of Cook and State of Illinois, have invented a certain new and useful Improvement in Processes of Manufacture of Dye-Soap, of which the following is a full, clear, concise, and exact description.

- 10 My invention relates to the manufacture of soap and is concerned particularly with the production of so-called "dye-soap", that is, a soap which carries an excess of dye for transfer to the fabric during washing.
- 15 It is the purpose of my invention to provide an improved dye-soap, a dye-soap in which the following matter is uniformly distributed, which is transparent, which does not lose its dye by ordinary handling and
- 20 which retains its cleansing properties without sacrificing effectiveness in its coloring property.

Broadly my invention contemplates the manufacture of dye-soap of vegetable oils, 25 tallow, and an excess of coloring matter; more specifically my invention contemplates the use of certain ingredients under certain conditions, and I have drawn the appended claim accordingly.

30 The specific compound and process which I shall describe, in order to instruct those skilled in the art, I have determined by careful experimentation and I shall proceed to set forth the precise manner in which I 35 produce the dye-soap of my invention, drawing the most specific of the appended claim toward the precise compound and process thus set forth.

I may state parenthetically that soap compounds high in percentage of alkali are not desirable, since the alkali tends to re-act with the added dye and destroy its coloring properties.

In the formation of the soap base I mix 45 10 kilos of cocoanut oil, ten kilos of castor oil and 8 kilos of tallow, saponification being then carried out by the use of 14 kilos of 38 degree Baumé caustic soda at a heat of 50 degrees centigrade, the mass being 50 constantly stirred at this maintained tem-

perature until it reaches a pasty consistency. 8 kilos of granulated sugar are then dissolved in $8\frac{1}{2}$ liters of water and this is added to the above mixture at 85 degrees centigrade. The compound is then neutralized by the proper addition of cocoanut oil and fatty acids and it is then ready for the reception of the dye. 55

The pigment is dissolved in a mixture consisting of 500 c. c. of water and 5 liters 60 of methyl alcohol. The soap base, as above prepared, is cooled to 60 degrees centigrade, when the dye mixture, thus prepared, is added with constant stirring. After the complete distribution of the dye has been 65 perfected, the compound is poured through a filter into frames and allowed to cool and thereupon the usual steps of slabbing, cutting and pressing may ensue.

The proportion of dye mixture to base 70 mixture is considerably in excess of any ordinary proportion to tint the soap, but the transparent quality is retained, thus producing a transparent dye-soap of the characteristics hereinbefore set forth. 75

The sugar clarifies the soap and the alcohol acts not only as a solvent for the dye but also to assist in this clarification, for which purpose glycerin may also be used.

The minimum percentage of dye is not to 80 be less than 15/100 of one per cent.

I claim:

The process of making a dye-soap which comprises saponifying a mixture of cocoanut oil, castor oil and tallow, in the proportion of 10, 10 and 8, respectively, with 38 degrees Baumé caustic soda in the proportion of 14 at 50 degrees centigrade, adding a solution of 8 kilos of granulated sugar in $8\frac{1}{2}$ liters of water at 85 degrees centigrade, 85 neutralizing the mixture with cocoanut oil and fatty acids, and then adding and mixing an alcoholic dye solution with the soap solution while the latter is at a temperature of about 60 degrees centigrade. 90

In witness whereof, I heretunto subscribe my name this 22nd day of October, A. D. 1917.

CLINTON S. ROBISON,
